UNITED STATES PATENT OFFICE.

HERO BRAT, OF GRAND RAPIDS, MICHIGAN.

GAME BOARD.

Application filed December 31, 1925. Serial No. 78,557.

This invention relates to game boards, and has for one of its objects the provision of a novel, simple and inexpensive device of this character on which a number of highly amusing games may be played.

With the foregoing and other objects in view, the nature of which will more fully appear as the description proceeds, the invention consists in the novel construction, combination and arrangement of parts hereinafter fully described and claimed, and illustrated in the accompanying drawing, wherein:

Figure 1 is a perspective view of a game board embodying my invention,

Figure 2 is a top plan view of the game board,

Figure 3 is a detail perspective view of one of the blocks used in connection with the game board when playing certain games thereon,

Figure 4 is a view in side elevation of one of the mallets used to propel the game pieces over the game board,

Figure 5 is a view in side elevation of one of the game pieces, and

Figure 6 is a detail sectional view taken on the plane indicated by the line 6-6 of Figure 2.

Corresponding and like parts are referred to in the following description, and designated in the several views of the accompanying drawing, by similar reference characters.

The game board is rectangular in contour, and comprises a panel 1 around which a rim 2 extends. It is provided at its corners with chutes 3 which are formed by short strips 4 and the sides of the rim 2. The chutes 3 are fully open at their upper sides and inner and outer ends. In the bottoms of the chutes 3 and adjacent their outer ends, are concave recesses 5 which are hereinafter referred to as "dimples". Deflectors 6 ex-

tending inwardly from the sides of the rim 2 and arranged at an angle of about eighty degrees with respect to the chutes 3, are adapted to carom the game pieces projected from the chutes onto the game board. The

board 1 is provided with inner and outer black rectangles 7, between which are eight white spots 8 and sixteen green spots 9, a white spot alternating with each pair of green spots. In the white spots 8 are concave recesses 8^a hereinafter referred to as "white dimples", and in the green spots 9 are concave recesses 9^a hereinafter referred to as "green dimples". The letters a, b, c and d which appear opposite the green dimples 9^a, indicate the order in which these dimples are to be played. A white spot 10 is located in the center of the rectangular series of green and white dimples and located in this spot is a concave recess 10^a hereinafter referred to as the "central white dimple". Within the rectangular series of green and white dimples, there is a rectangular series of concave recesses 11, within this series of recesses is a rectangular series of similar recesses 12, between the deflectors 6 and sides of the rim 2 are similar recesses 13 and on the side of the rectangles 7 and at the corners thereof are similar recesses 13^a, all of which are hereinafter referred to as "cups". The values of the cups 11, 12 and 13 in computing the score of one of the games are indicated by numerals adjacent the cups.

The game board is equipped with spherical game pieces 14, mallets 15 and blocks 16. The mallets 15 each consists of an elastic handle 15^a and a spherical head 15^b. The blocks 16 are each provided with an inclined end 16^a.

The rim 2 extends above the panel 1 for a distance greater than the diameter of the game pieces 14, the dimples 5, 8^a and 9^a are just deep enough to prevent casual movement of any game pieces placed thereon, and the pockets 11, 12 and 13 have a depth equal to the radius of the game pieces to retain the game pieces placed therein against casual and manual movement.

Three games entitled respectively "Guidum", "Pigeonhold" and "Marbleshot" may be played on the game board.

The game of "Guidum" may be participated in by two, three or four players, and

each is equipped with a mallet 15 and a game piece or marble 14. The score of the game may be set by the players as high or as low as wished or it may be agreed upon among 5 the players that the one making the highest score within a certain time wins the game. One of the players starts the game by placing his marble 14 in the dimple 5 of one of the chutes 3. He then either snaps the marble with his finger or with his mallet. If 10 the latter is used the handle 15^a is held between the fingers of the right hand and the head 15^b between the fingers of the left hand, and after placing the handle under tension 15 the head 15^b is released with the result that the marble is impelled onto the board in the direction of one of the deflectors 6. The marble caroms from this deflector onto the board, and if it stops in one of the white 20 dimples 8^a or in one of the green dimples 9^a or in the central white dimple 10^a the player is entitled to another turn. If, however, the marble stops in one of the cups 11, 12 or 13 the player scores a point numerical- 25 ly commensurate with the number appearing opposite the cup in which the ball comes to rest. The next player now takes his turn and so on until the game is finished. The player who makes the score first or makes 30 the largest score within the time set for the playing of the game wins the game.

The game of "Pigeonhold" is adapted to be played by two persons, and each is provided with a mallet and three of the game pieces which in this instance are called 35 "bumpers". The bumpers of one player are red and those of the other blue. One white marble called the "pigeon", four of the blocks 16, and sixteen clay marbles called 40 "megs" are placed on the board when playing this game. The players seat themselves at opposite sides of a table and place the game board between them in such a manner that diagonally opposite corners of the game 45 board will be opposite them. Blocks are placed in the chutes 3 opposite the players in the manner suggested by dotted lines in Figure 2 to provide pockets or traps 16^b. The other chutes are closed by blocks which 50 are placed therein in the manner suggested in this figure. The pigeon is placed in the central white dimple 10^a. Each player places one of his bumpers on the white dimple 8^a in the corner nearest him and one in 55 each of the next nearest of the white dimples 8^a. A clay marble is placed in each of the cups 11, 12, 13 and 13^a. The player who first succeeds in placing the pigeon in the trap of his opponent wins the game. 60 The arrangement of the clay marbles about the pigeon, requires the exercise of a high degree of skill to effect the placing of the pigeon in the trap of an opponent. To do this a player must use only his own bumpers 65 and strike his bumpers with the mallet only.

The game of "Marbleshot" is adapted to be played by two persons. The idea of this game is to be a sharpshooter. One player has one set-up marble and the other has sixteen megs. To win a degree one of the players must have all the megs and the set-up marble too. Two games must be played for a set, the players alternating set-ups. One set is played for each degree. The degrees of honor to be won are:

70 1st degree, crackshot private, from a to c.
2nd degree, corporal of the bull's eye squad, from a to d.

75 3rd degree, captain of the sharpshooters, from a to b.

80 4th degree, master marksman, from a to a.

85 5th degree, marbleshot ace, given only to the player that wins all the games in all the sets.

90 That is: to obtain the degree of marble-shot ace one of two players must win eight games making two games for each degree. This degree is rarely won. Both players have equal chances and if each wins a game of each set they will both have the same degrees and honors.

95 To play, one player puts his set-up in the dimple called for by the second letter mentioned in the degree list, while the other player rolls his megs from the letter (a). The megs are always rolled from the (a) dimple. The meg is taken between the thumb and first and second fingers and rolled at the set-up from the (a) dimple. If it does not strike, the next one is rolled, and so on until the set-up is struck. The first player then gets the set-up and sets it and the second player rolls at the set-up with the megs he has taken. The one succeeding in getting all the megs and the set-up, wins the first game of the set. The set-up and the megs are then exchanged and the second game of the set is played from the same positions on the opposite sides of the board. If two players tie they 100 continue with the following sets until the end and then start the whole game over. The tie may be broken when one player wins more degrees than the other, but he gets the fifth degree only when he wins the two 105 games of each set for the fourth degree.

110 The other side of the game board may be constructed as shown and described in my copending application, filed 12th day of December 1925, and serially numbered 115 75,022.

120 What is claimed is:—

125 1. A game board comprising a rectangular panel provided with recesses, a rim surrounding the panel, a chute in each corner of the game board, and deflectors angularly related to the chutes.

130 2. A game board provided with a rectangular series of recesses and a recess located centrally within said series of recesses, and

said board being provided within and without said rectangular series of recesses with other recesses greater in depth than the first named recesses.

5 3. A game board provided with a rectangular series of recesses and a recess located centrally within said series of recesses, said

board being provided within and without said rectangular series of recesses with other recesses greater in depth than the first named recesses, and diagonally opposed traps on the game board.

In testimony whereof I affix my signature.

HERO BRAT.
